UNITED STATES PATENT OFFICE.

JOSEPH N. MAHONEY, OF WILKINSBURG, PENNSYLVANIA, ASSIGNOR TO WESTINGHOUSE ELECTRIC AND MANUFACTURING COMPANY, A CORPORATION OF PENNSYLVANIA.

CIRCUIT-INTERRUPTER.

1,241,534.

Specification of Letters Patent.

Patented Oct. 2, 1917.

Application filed October 15, 1914. Serial No. 866,796.

To all whom it may concern:

Be it known that I, JOSEPH N. MAHONEY, a citizen of the United States, and a resident of Wilkinsburg, in the county of Allegheny and State of Pennsylvania, have invented a new and useful Improvement in Circuit Interrupters, of which the following is a specification.

My invention relates to circuit interrupters and particularly to interrupters of the reactance type.

The object of my invention is to provide an improved and simplified type of reactance circuit interrupter.

When a high-voltage circuit is opened and closed, the transient wave or surge that is set up must be dissipated in order to protect the circuit from undue oscillations and disturbances. My copending U. S. applications, Serial Nos. 784,085, and 784,083, filed August 11, 1913, disclose circuit interrupters for accomplishing this result. In circuit interrupters of this type, a reactor is inserted in the circuit before it is interrupted and before it is closed for the purpose of dissipating the surges that are incident to such operations. These devices are efficient but they are expensive to construct by reason of the complicated mechanism necessary to provide the correct time interval between the operation of the different parts of the same.

My present invention provides a circuit interrupter of the reactance type that does not require a complicated operating mechanism since the movable contact members of the same are operated simultaneously. I employ an ordinary three-pole circuit interrupter and I mount the reactor between the terminals of one pole of the same and connect the reactor in shunt relation to the contact members of another pole. It has been found that, with this construction, a circuit may be interrupted with a minimum amount of disturbance.

Figure 1 of the accompanying drawings is a rear view, partially in elevation and partially in section, of a circuit interrupter embodying my invention; Fig. 2 is a side view, partially in elevation and partially in section, of the circuit interrupter shown in Fig. 1, and Fig. 3 is a diagrammatic view of a circuit interrupter embodying my invention.

55 A generator 1 supplies current to an elec-

trical load 2 through a conductor 3 in which is connected a circuit interrupter 4, embodying my invention.

The circuit interrupter 4 is mounted on a panel 5 and comprises a bracket 6 that supports an oil-containing receptacle 7 in which is disposed stationary contact members 8 and 9 and movable bridging members 10 and 11 to coöperate therewith. The stationary contact members 8 and 9 are mounted on the lower ends of a plurality of stationary terminal members 12. A reactor 13 is mounted on the lower ends of two of the stationary terminal members 12, and the terminal members on which it is mounted are permanently connected, in shunt relation, to the pair of terminal members 12 on which the stationary contact members 9 are mounted. The bridging members 10 and 11 are supported by rods 14 and 15 that are operatively connected together by a bar 16. A link 17 is pivotally connected, at one end, to the bar 16 and, at its other end, to a lever 18 that is pivotally mounted on the bracket 6. A bell-crank lever 19 is pivotally mounted on a pin 20 and is operatively connected, by a link 21, to the lever 18. A bifurcated lever 22 is also pivotally mounted on the pin 20 and is disposed on two sides of one arm of the bell crank lever 19 to constitute therewith a compound operating lever. A latch member 23 is pivotally mounted on the lever 22 and is adapted to engage the lever 19 for the purpose of latching the said levers normally together. A tripping device 24, comprising a magnet coil (not shown) and a movable core member 24^a, is mounted on the front of the panel 5. The movable core member 24^a is adapted to engage one arm of the latch 23 to trip the lever 19 free from the lever 22 under predetermined load conditions.

Assuming that the circuit interrupter 4 is in the position shown in Fig. 3 of the drawing and that it is desired to complete the circuit through the conductor 2, my invention operates as follows:

The operating lever 22 is moved upwardly until the latch 23 engages the lever 19, then it is moved downwardly to cause the bridging members 10 and 11 to engage their respective stationary contact members 8 and 9. When the movable and stationary contact members are being engaged, the reactor 13 is rendered inoperative by reason of the

105

110

low resistance of the bridging member 11 connected in shunt relation thereto. However, this is not detrimental, as very little surge is perceptible when the circuit is closed.

If a surge or an overload on the line causes the current traversing the conductor 3 to rise to such a value that the winding of the tripping device 24 becomes sufficiently energized, the movable core member 24* will engage the latch 23 to release the bell crank lever 19. The lever 19 will turn upon the pin 20 to allow the bridging members 10 and 11 to be disengaged from their respective stationary contact members 8 and 9. A rush of current or a surge will traverse the gap between the movable and the stationary contact members when they are being disengaged, but this rush of current must necessarily traverse the reactor 18 and be thus reduced and consequently dissipated so that no undesirable effects will be noticeable in the circuit.

While I have shown my invention in a simple and preferred form, it is not so limited, but is capable of various modifications within the scope of the appended claims.

I claim as my invention:

1. A circuit interrupter comprising two sets of movable and stationary contact members connected in series relation, means for so connecting the said movable contact members mechanically together that they open simultaneously and a reactor connected in shunt relation to one of said sets of stationary contact members.

2. A switch for an electric circuit comprising a plurality of sets of coöperating contact members connected in series relation to the circuit, means for opening the sets simultaneously and a reactor connected in shunt relation to one of said sets of contact members.

3. A switch for an electric circuit comprising two sets of stationary and movable contact members connected in series relation to the circuit, means for causing the said movable contact members to open at the same time and a reactor connected in shunt relation to one of said sets of stationary contact members.

4. A switch for an electric circuit comprising a plurality of sets of contact mem-

bers connected in the said circuit, means for opening the said sets of contact members simultaneously and an energy-absorbing device connected in shunt relation to one of said sets of contact members.

5. A switch for an electric circuit comprising a plurality of sets of movable and stationary contact members connected in series relation to the said circuit, means for so operatively connecting the movable contact members together that they open simultaneously, and an energy-absorbing means connected in shunt relation to one set of the said stationary contact members.

6. In an electrical circuit, the combination with a plurality of sets of movable and stationary contact members, means for opening the movable contact members simultaneously, and means connected in shunt relation to the stationary contact members of one of said sets of contact members for dissipating the energy incident to the interruption of the said circuit.

7. An interrupter for an electric circuit comprising a plurality of coöperating contact members connected in series relation to the circuit, means for effecting the simultaneous opening of the contact members and means connected in shunt relation to certain of the contact members for dissipating the energy incident to the interruption of the circuit.

8. A circuit interrupter comprising a plurality of sets of coöperating contact members connected in series with the circuit to be protected, means for causing the sets to be opened simultaneously and an energy-absorbing device connected in shunt relation to one of the said sets.

9. A switch for an electric circuit comprising a plurality of sets of coöperating contact members connected to the circuit, means for causing the sets to be opened simultaneously and an energy-absorbing device connected in shunt relation to one of the said sets.

In testimony whereof, I have hereunto subscribed my name this 29th day of September, 1914.

JOSEPH N. MAHONEY.
